UNITED STATES PATENT OFFICE

114,144

DESIGN FOR A SHAVING IMPLEMENT

Henry T. Schiff, Chicago, Ill.

Application November 14, 1938, Serial No. 81,077

Term of patent 7 years

To all whom it may concern:

Be it known that I, Henry T. Schiff, a citizen of the United States of America, residing at 429 South Ashland Avenue, Chicago, Illinois, have invented a new, original, and ornamental Design for a Shaving Implement, of which the following is a specification, reference being had to the accompanying drawing, forming a part thereof.

Fig. 1 is a front view; Fig. 2 a back view; and Fig. 3 is a side view of my shaving implement.

I claim:

The ornamental design for a shaving implement, substantially as shown.

HENRY T. SCHIFF.
